(57) **CLAIM**

The ornamental design for a license plate frame, as shown and described.

DESCRIPTION

FIG. 1 is a perspective front view showing our new design for a license plate frame.

FIG. 2 is a magnified view of a portion of the license plate frame shown in FIG. 1.

FIG. 3 is a front view of the license plate frame of the present invention.

FIG. 4 is a back view of the license plate frame of the present invention.

FIG. 5 is a right side view of the license plate frame of the present invention, the left side view being the mirror image thereof.

FIG. 6 is a top view of the license plate frame of the present invention, the bottom view being the mirror image thereof.

FIG. 7 is a front view showing a second embodiment of our design for a license plate frame, with the belt buckle in a different location on the frame than shown in FIG. 1.

FIG. 8 is a front perspective view of a third embodiment of our design for a license plate frame, with the outer row of ornamentation moved closer to the inner row of ornamentation than in the configuration shown in FIG. 1 and additional ornamentation applied to the buckle.

FIG. 9 is a magnified view of a portion of the license plate frame shown in FIG. 8.

FIG. 10 is a front view of the license plate frame shown in FIG. 8.

FIG. 11 is a back view of the license plate frame shown in FIG. 8.

FIG. 12 is a right side view of the license plate frame shown in FIG. 8, the left side view being the mirror image thereof.

FIG. 13 is a top view of the license plate frame shown in FIG. 8, the bottom view being the mirror image thereof; and, FIG. 14 is a fourth embodiment of our design for a license plate frame, with the belt buckle shown in a different location on the frame than shown in FIG. 8.
